SCREW CONVEYING STEAM DISTILLING
APPARATUS FOR POMACE

Ernest Kurt Metzner, Los Angeles, Calif.

Application September 22, 1945, Serial No. 617,996

4 Claims. (Cl. 202—176)

1

This application is a continuation in part of my application Serial Number 459,178, filed September 21, 1942, and now Patent Number 2,387,165, issued October 16, 1945. Application Serial Number 459,178, is a division of my earlier application, Serial Number 424,161, Patent 2,359,929, October 10, 1944.

This invention relates to a continuous process for the recovery of the ethyl alcohol value in fruit pomace and like materials. The terms pomace and fruit pomace are each used herein in a broad sense as applying not only to the usual grape pomace but to other materials derived from fermentation processes practiced upon various fruits and vegetables to produce ethyl alcohol by fermentation.

My aforementioned patents deal with the recovery of tartrate values from pomace. In accordance with this invention, I provide a novel apparatus and process for the recovery of the ethyl alcohol value in the pomace. Heretofore the alcohol present in these materials has been deemed so difficult of recovery that it has been neglected. This is understandable for the pomace in a hard, packed mass of skins, seeds, stems and pulp containing a relatively low alcohol content. I have found that by continuously working the pomace mass so as to loosen it and render it vapor permeable and by continuously discharging steam or other hot gas into the loosened mass of pomace to raise the temperature to a point whereat the alcohol vaporizes readily, the alcohol is vaporized and swept out of the mass. It is not necessary to raise the temperature of the pomace to above the boiling point of the alcohol because the steam or other hot gas permeating the mass sweeps the alcohol vapor out of the mass. To practice this process, I have provided a novel apparatus in which the pomace is preferably worked by screw conveyor flights which keep the mass loose and vapor permeable.

It is the generally broad object of the present invention to provide a novel apparatus for recovery of alcohol from pomace.

A further object of the present invention is to provide a novel process for the recovery of ethyl alcohol from a mass of pomace.

The invention includes other objects and features of advantage, some of which, together with the foregoing will appear hereinafter wherein the present preferred form of apparatus for practicing the process of the invention is disclosed. In the drawings accompanying and forming a part hereof—

2

Figure 1 is a side elevation, partly in section, illustrating the construction of the apparatus.

Figure 2 is an end view of the apparatus shown in Figure 1.

Figure 3 is an enlarged cross section showing the pair of conveyor flights, the pomace supporting shelf, the steam discharge pipe and, diagrammatically, the manner in which the cooperating screw conveyor flights work the pomace mass.

Referring to the drawings, I provide a suitable base or support 6 on which is mounted the alcohol vapor extraction vessel 7. Positioned transversely of vessel 7 are several pomace supporting shelves 8, 9 and 10. As appears in Figure 3, each pomace support shelf is arcuately formed along each longitudinal side 11 to fit the adjacent portion of the parallel screw conveyor flights 12 and 13 which extend along each shelf. Screw conveyor flights 12 and 13 are each mounted upon a shaft 14 and on a shaft 15. Shelf 8 extends from the right hand side of vessel 7 (Figure 1) across the vessel, terminating short of the other end of the vessel so that the material advanced along the shelf by the conveyor flights falls off the end of the shelf and onto the immediately adjacent but lower conveyor flights and their cooperative shelf 9. Shelf 10, in turn, extends from the left hand side of vessel 7 (Figure 1) toward the other side of the vessel so that that the material transported thereover by the conveyor flights is discharged on to the pair of immediately adjacent but lower conveyor flights positioned just above shelf 10. This construction enables the length of vessel 7 to be reduced as compared to the length required if a single shelf was employed with a single pair of flights. In addition, the pomace falling on to another pair of conveyor flights works the pomace additionally and enables it to be further loosened.

Shafts 14 and 15 for each conveyor flight are supported in suitable bearings carried in the end walls of vessel 7. Mounted upon the left hand end of each of these shafts are cooperating and inter-engaged gears 16 (Figure 1). The several flights are driven in a timed relation by motor 17 mounted upon an extension 18 on support 6. A chain 21 is trained about a sprocket 19 on the motor shaft and about a sprocket 22 on shaft 14 in the lowermost conveyor flight. Because of the inter-engagement of the gears on the other end of shafts 14 and 15, the cooperatively adjacent flight is driven in a timed relationship. A sprocket 23 on shaft 14 drives a chain 24 provided about sprocket 26 on the next immediately adjacent shaft 14 while sprocket 28 on shaft 15

in the intermediate flight drives chain 29 and, in turn, sprocket 31 on uppermost shaft 15. In this way, several flights are driven with a single motor and in a timed relationship and, with all flights having the same pitch, the pomace moves continuously through the vessel 1 at a uniform rate.

Means are provided for discharging pomace to be treated into vessel 1. To effect this a superstructure or frame 41 is mounted upon an upper portion of the vessel 1 to support a hopper 42 and a pipe 43 which extends downwardly from the hopper into the vessel 1. A screw conveyor flight 44 is positioned in pipe 43, terminating above the end of the pipe so that a solid plug of pomace fills and seals the end of the pipe. The screw flight, which can be vertical or horizontal, is mounted upon a shaft 46 supported in suitable bearings 47 in the frame. A mitre gear 49 is mounted upon shaft 46 and is driven by a mitre gear 51 on shaft 52 of motor 53.

To close discharge pipe 43 and prevent vapors from passing out through this pipe when pomace is not being discharged, a shaft 56 is mounted transversely of vessel 1. On that end of the shaft which projects from the vessel, an arm 57 is mounted carrying a weight 58. Within the vessel, a door 59 is mounted on shaft 56 to extend across pipe 43. Material forced through the pipe 43 by the screw conveyor 44 moves the door out of the way so that the material is free to fall down upon the immediately adjacent screw conveyor flights. When material is not being discharged, weight 58 is effective to swing the door into sealing position across the end of the pipe 43.

To remove vapors, vapor chest 61 is provided on the upper portion of the vessel and is connected by a pipe 62 to an alcohol-water condenser 63 through which a suitable heat exchange coolant is passed in a heat exchange relationship. A sight gauge 64 is provided on the side of the condenser and, as desired, the condensed aqueous alcohol solution is drawn off through pipe 66 into an alcohol receiving tank 67 for further processing or concentration.

Between each screw conveyor flight 12 and 13 is provided a pipe 71, their being three pipes each connected to a common header and by means of this to a supply of steam or other hot gas. Each pipe has a plurality of jet-like openings 74 along the pipe to release the hot gas into the pomace. With pomace discharged substantially continuously from hopper 42, the compact fibrous mass of seed, stems, skin and pulp is broken and loosened by the continuous working between the supporting shelf and the several pipes. In Figure 3 I have shown this diagrammatically; the two conveyor flights throw the pomace toward the middle of the shelf and build up a loose mass of material into which the hot fluid is released in jet form to assist in breaking up the mass and vaporizing the alcohol by heating the pomace to facilitate vaporization and, because of the volume of steam, sweeping out of the pomace any alcohol vapors arising from the pomace so that by the time pomace reaches discharge pipe 72 it is substantially free of alcohol. The pomace discharged through pipe 72 is admitted to a tank 73 for tartrate extraction according to my aforementioned patents.

Pipe 72 extends below the level of liquid in tank 73 and the pipe is thus sealed against vapor loss.

It is a feature of this invention that pomace can be processed for its alcohol content without

any prior grinding or other comminution operation. So long as the pomace can be fed into the screw 43 it can be de-alcoholized.

I claim:

5 1. An apparatus for recovery of the alcohol in pomace comprising a vessel, a plurality of pairs of screw conveyor flights arranged horizontally in said vessel with the flight in each pair in a side by side relationship and at substantially the same elevation, the different conveyor flight pairs being positioned at different elevations in said vessel with each pair arranged to deliver material to a next lower adjacent pair, a material support shelf positioned beneath each pair of flights to support material moved by said pair of flights, means for rotating each screw conveyor in each pair in a direction opposite to the direction of rotation of the other flight of the pair and with the adjacent edges of the two flights moving upwardly and away from the cooperatively adjacent material support shelf to move material along the shelf and to maintain a mass of material piled up on and between the cooperating adjacent edges of the flights, a pipe arranged along each shelf between each pair of conveyors and having a plurality of jets along the length thereof to release a gas into the mass of material piled up between the pair of flights, and means for discharging material to the uppermost conveyor pair.

10 2. An apparatus for recovery of the alcohol in pomace comprising a vessel having opposite first and second vertical end walls, a plurality of pairs of screw conveyor flights arranged horizontally in said vessel with the flight in each pair in a side by side relationship and at substantially the same elevation, the different conveyor flight pairs being positioned at different elevations in said vessel with each pair arranged to deliver material to a next lower adjacent pair, a plurality of material support shelves extending horizontally from only one of said end walls, each shelf being positioned cooperatively beneath one pair of flights to support material moved by said pair of flights, means for rotating each screw conveyor 15 in each pair in a direction opposite to the direction of rotation of the other flight of the pair and with the adjacent edges of the two flights moving upwardly and away from the cooperatively adjacent material support shelf to move material along the shelf and to maintain a mass of material piled up on and between the cooperating adjacent edges of the flights, a pipe arranged along each shelf between each pair of conveyors and having a plurality of jets along the length thereof to release a gas into the mass of material piled up between the pair of flights, and means for discharging material to the uppermost conveyor pair.

20 3. An apparatus for recovery of the alcohol in pomace comprising a vessel having opposite first and second vertical end walls, a plurality of pairs of screw conveyor flights arranged horizontally in said vessel with the flight in each pair in a side by side relationship and at substantially the same elevation, the different conveyor flight pairs being positioned at different elevations in said vessel with each pair arranged to deliver material to a next lower adjacent pair, a plurality of material support shelves extending horizontally in said vessel from only one of said end walls and terminating short of the other end wall, the plurality of shelves being staggered in said vessel with each shelf positioned cooperatively below a pair of flights to support material moved by said pair of flights, means for rotat-

ing each screw conveyor in each pair in a direction opposite to the direction of rotation of the other flight of the pair and with the adjacent edges of the two flights moving upwardly and away from the cooperatively adjacent material support shelf to move material along the shelf from the forward end to the rearward end of the shelf and to maintain a mass of material piled up on and between the flights, a pipe arranged along each shelf between each pair of conveyors and having a plurality of jets along the length thereof to release a gas into the mass of material piled up on and between the pair of flights, and means for discharging material to the uppermost conveyor pair adjacent to the forward end of the cooperatively positioned shelf.

4. An apparatus for treating pomace comprising a vessel, a plurality of substantially horizontal trays positioned in said vessel with one tray below another and in a staggered relationship, a pair of screw conveyors extending cooperatively along each tray, means for rotating each of said pair of conveyors to move material in the same direction along the cooperatively positioned tray and to build up and maintain a mass of material on and between the cooperatively adjacent edges of the flight pair, a vapor discharge pipe extending horizontally along each tray between the pair of conveyors thereon to discharge vapor into the mass of material between the pair of screw conveyors, and means for discharging

material onto the forward end of the pair of conveyors on the uppermost tray.
